Design No. 12,842, dated April 4, 1852.

DESIGN FOR WALL-PAPER.

UNITED STATES PATENT OFFICE.

CAROLINE TOWNSEND, OF ALBANY, ASSIGNOR TO WARREN, FULLER & CO.,
OF NEW YORK, N. Y.

DESIGN FOR WALL-PAPER.

SPECIFICATION forming part of Design No. 12,842, dated April 4, 1882.

Application filed February 3, 1882. Term of patent 3½ years.

To all whom it may concern:

Be it known that I, CAROLINE TOWNSEND, a citizen of the United States, residing at Albany, in the county of Albany and State of New York, have invented and produced a new and original Design for Wall-Paper, of which the following specification is a clear description, reference being had to the accompanying drawing, forming part thereof.

10 The said drawing represents an elevation of a section of my design for wall-paper.

The transverse bands or belts A A' A² A³ A⁴ A⁵ are quite narrow—say one or two inches wide, more or less—and they are enriched with 15 geometrical figures in oval or circular forms, which represent a jewel-setting. The two lower of these belts, A and A', are placed respectively at the bottom and top of a narrow sub-base paneling, B, the said paneling B being filled with pointed geometrical figures similar to those shown and described in the paneling D, hereinafter described. The next two of these bands moving upward from the bottom of the section are lettered A² and A³, 20 and these respectively form the lower and upper boundaries of the intermediate paneling, D, which is enriched with pointed geometrical figures that nearly fill the field of the panel. The other two of these transverse bands—viz., 25 30 A⁴ and A⁵, respectively—form the bottom and

top boundaries of the cornice-field F. The central and large panel or field of ornament, E, is placed between the bands A³ and A⁴, and this panel, as well as the cornice-panel F, is richly ornamented with foliation and flowers 35 aesthetically arranged. The lower of these panels is shaded somewhat darker or deeper than the upper or cornice panel, F, and the floral ornaments of the upper panel are formed on circular shields. The paneling C is foliated in 40 dark figures on a dark and mottled background.

The ornamentation and lining of this design may be printed or painted in any desired coloring or any desired color of background.

Having described my invention or design, I claim—

The ornamental design for wall-paper or paper-hangings, consisting of the transverse bands or belts A, A', A², A³, A⁴, and A⁵, and 50 the transverse or horizontal panelings B and D, with their ornamentations of geometrical figures, and the intervening panelings, C, E, and F, with their foliated enrichments, designed and elaborated substantially as described.

CAROLINE TOWNSEND.
